UNITED STATES PATENT OFFICE.

FRANK E. STAUFFER, OF CHICAGO, ILLINOIS.

BEER-BUNG.

No. 841,848.

Specification of Letters Patent.

Patented Jan. 15, 1907.

Application filed July 20, 1904. Serial No. 217,416.

To all whom it may concern:

Be it known that I, FRANK E. STAUFFER, a citizen of the United States, residing at Chicago, in the county of Cook and State of Illinois, have invented certain new and useful Improvements in Beer-Bungs, of which the following is a specification.

This invention is primarily designed for use in connection with barrels, half-barrels, and other-sized packages containing beer, but can be used in connection with packages containing other liquor and liquids.

The objects of the invention are to furnish a bung which can be inserted in the package and remain therein as a fixture and which is adapted to receive a closing-plug or stopper which can be forced out by the insertion of the draft-tube without any great trouble and inconvenience to enable the closing-plug or stopper to be sealed in place effectually against the escape of the liquid and pressure when the package is full and is stored away or shipped for use; to retain the closing-plug or stopper nominally by a packing or gasket adjacent to its lower end and to seal the plug or stopper by a packing or gasket adjacent to its upper end, so arranged as to release the seal and allow the plug or stopper to be forced out through the entering of the draft-tube into the package for use; to construct a bung having an outer shell with an interior chamber and provided with a bottom having therein a hole for the passage of the draft-tube and locating in the chamber of the outer shell a lower packing-ring or gasket engaged by a follower threaded into the shell on which rests an upper packing-ring or gasket compressed by a follower; to allow the upper packing-ring or gasket to be sufficiently released from compression by partially withdrawing its follower without breaking the seal sufficient for the escape of the beer or other liquid and at the same time permit the closing-plug or stopper to be forced out with the entering of the draft-tube into position for use, and to improve generally the construction and arrangement of the elements which enter into the formation of the bung.

The invention consists in the features of construction and combination of parts hereinafter described and claimed.

In the drawings, Figure 1 is an elevation of the bung of the invention inserted in place in the head of a package, the head being in section and broken off on each side of the

bung; Fig. 2, a sectional elevation of the bung with the closing-plug or stopper therein and the packing-rings or gaskets compressed around the plug or stopper; Fig. 3, a sectional elevation similar to Fig. 2 with the closing-plug or stopper removed and the upper packing-ring or gasket released from compression; Fig. 4, an elevation of the bung, showing the draft-tube forcing the closing-plug or stopper out of the bung; Fig. 5, an elevation of the bung and draft-tube with the draft-tube in position and broken out; Fig. 6, a sectional elevation of the upper end of the draft-tube, showing the independent passage or conduit for admitting air or carbonic-acid gas or other pressure-producing medium; Fig. 7, an elevation of one of the followers for compressing the packing-rings or gaskets; and Fig. 8, a detail showing the coupling-head for the upper end of the draft-tube with the nipple for attaching the hose through which compressed air or carbonic-acid gas is allowed to flow and enter the conduit in the draft-tube, the hose not being shown.

The bung is formed of an outer shell or wall A, made of any suitable metal or material. This shell or wall has on its exterior in the construction shown a screw-thread, by which the bung in its completed condition can be screw-threaded into the head or other portion of the package or can be screw-threaded into a metallic bushing in the head or other portion of the package; but in place of having a screw-thread on the exterior of the shell or wall such exterior can be left smooth and the bung as a whole driven or otherwise forced into place. The shell or wall A has an interior chamber A', which is open at the top and is closed at the bottom by a wall a², having therein a hole a³ for the passage of the closing-plug or stopper and the draft-tube, and the wall a² is cut away around the hole a³, so as to form a shoulder a⁴ and furnish an annular recess or depression to receive the lower packing-ring or gasket in the construction shown.

The interior face of the shell or wall A has a screw-thread a' extending from the upper end downwardly. The chamber A' has entered thereinto a follower B, having a peripheral thread b to engage the thread a' for advancing and withdrawing the follower, and the under face of the follower B abuts against the upper face of a packing-ring or gasket b' in the recess or depression of the shoulder a⁴, so that with the advance of the follower the

packing-ring or gasket will be compressed sufficiently to engage the face of the closing-plug or stopper and hold the plug or stopper nominally in position. The chamber A' has entered thereinto a second follower C, the periphery of which has a screw-thread c to engage the screw-thread a' for advancing and receding the follower, and the under face of the follower C engages a packing-ring or gasket c', resting on the upper face of the follower B, so that by advancing the follower C the packing-ring or gasket c' will be tightly compressed around the closing-plug or stopper and effectually seal the bung against the escape of the beer or other liquid and the compressed air or other pressure-supplying medium. The follower C is the active follower, as the follower B when once set to compress the packing b' remains set, except in case of wear of the packing or gasket, when the follower B is advanced so as to compress the packing or gasket and cause the same to again nominally retain the closing-plug or stopper in position. The active follower C is advanced and receded for compressing and releasing the packing-ring or gasket c', and as the repeated turning of the follower C would wear more or less on the end face of the gasket c' in order to prevent such wear a metal washer or a washer of any suitable material c² is inserted between the follower C and the packing-ring or gasket c', which washer c² serves to protect the end face of the packing-ring or gasket in advancing and receding the follower. The follower B has in its upper face notches or recesses b² to receive a suitable wrench or tool, by which the follower can be turned into and out from the chamber A' or can be turned to act and properly compress the packing-ring or gasket b' around the closing-plug or stopper, and the follower C has in its upper face notches or recesses c² to coat with a spanner-wrench or other tool or instrument by which the follower can be turned into and out of the chamber A' or can be turned to advance and recede the follower for compressing and releasing the packing-ring or gasket c', as required for sealing the bung or for allowing the closing-plug or stopper to be forced or driven out.

The closing-plug or stopper D can be made of wood, preferably circular in cross-section, and this plug or stopper is inserted in a hole d therefor, which hole is formed by a central hole in the followers, gaskets, and washer, as shown in Fig. 3. The lower packing-ring or gasket b' is compressed by the follower B, so that it will nominally hold the closing-plug or stopper D in position, without, however, fully sealing the plug or stopper, as the compression must not be so great as to prevent the plug or stopper from being readily forced out by inserting the draft-tube, which tube is entered through the hole d for the plug or stopper. The lower packing-ring or gasket when once set remains in that position, as the diameters of the closing-plugs or stoppers are the same, so that if the packing-ring or gasket is adjusted to nominally hold one plug or stopper it will hold successive plugs or stoppers until it becomes worn, in which case the follower B is advanced sufficiently to further compress the packing-ring or gasket and have the plug or stopper retained nominally in position by the lower ring or gasket. The plug or stopper is effectually sealed and firmly held in position by the gasket c', for which purpose this packing-ring or gasket c' is compressed by the advance of the follower C until an effectual seal is furnished thereby around the closing-plug or stopper. The filled package has the packing-ring or gasket c' tightly compressed around the closing-plug or stopper, and for beer and other liquids requiring a stamp such stamp is to be placed over the outer end of the bung, as usual.

The draft-tube E can be made of suitable metal or material, as usual, and of a diameter to pass through the hole d in the bung for the closing-plug or stopper and of a length to suit the package with which it is used, so that its lower end will come to the bottom, or nearly so, of the package for the beer or other liquid to be drawn out through the openings e in the bottom of the draft-tube and through the passage in the draft-tube, as usual. It is essential in drawing beer that pressure should be supplied in order to maintain the pressure in the package for drawing off the beer, and the pressure can be compressed air, carbonic-acid gas, or other pressure-producing medium. The pressure should be entered as near the bottom or lower end of the bung as possible, and for this purpose the draft-tube E has located therein near its upper end an independent tube or conduit F, which tube or conduit has therein a passage f, having at its lower end an opening f' through the wall of the draft-tube, and having at its upper end an opening f² through the wall of the draft-tube in the construction shown in Figs. 5 and 6. The draft-tube on the side adjacent to the opening f² has secured thereto in the arrangement of Figs. 5 and 6 a block or head G, having therein a passage g, which communicates with the opening f², and projecting up from the block or head G is a nipple g' for the attachment of a supply-hose leading to a source of compressed air, carbonic-acid gas, or other pressure medium, (not shown,) through which nipple the passage g is continued, so that the pressure medium can flow through the passage g, opening f², passage f, and opening f' into the package and maintain the required pressure in the package.

The coupling-head is omitted from the upper end of the draft-tube E in the construction shown in Figs. 5 and 6; but a coupling-

head H is to be attached to the upper end of the draft-tube, as shown in Fig. 8; said coupling-head having a shell h, in which is located a controlling-valve plug h', operated by a handle h², as usual. The block or head G instead of being attached to the side of the draft-tube, as in, Figs. 5 and 6, can be attached to the side of the coupling-head, as shown in Fig. 8, the block having a nipple g' and a passage g in communication with the passage f, as in Fig. 6, for admitting pressure to the package.

In use the shell or wall A is inserted in the head of the barrel, keg, or other package with which it is connected for its upper or outer end to be flush, or nearly so, with the outer face of the head or other portion of the package and for its lower or inner face to project preferably beyond the face of the head or other portion of the package. The inner or lower packing-ring or gasket b' is inserted in place, and the follower B is screwed into the interior of the wall or shell until it engages and compresses the packing-ring or gasket around the closing-plug or stopper D, which is inserted through the packing-ring or gasket, so as to be held in place by the compression of the ring or gasket. This initially sets the inner or lower packing-ring or gasket in proper relation to receive the closing-plugs or stoppers one after another and so that the pressure of the ring or gasket does not interfere with the driving or forcing out of the plug or stopper by and through the entering of the draft-tube. The packing-ring or gasket c' is then inserted in place around the plug or stopper for its end face to abut against the end face of the follower B, and the follower C is then screwed in place to compress the packing-ring or gasket c' around the plug or stopper and tightly seal the plug or stopper when inserted against the escape of the beer or other liquid and the escape of pressure and holding the plug or stopper firmly in position, with its outer end flush, or nearly so, with the outer face of the shell or wall and with its inner end entered into the opening a³ in the bottom wall a² of the shell or wall A of the bung. The package is then in condition to be filled with the beer or other liquid, and when filled, if to be stamped, the stamp is placed over the outer end of the bung, as usual.

The closing-plug or stopper D is entered into the hole d therefor in the several packing-rings and followers and the washer c², and when the uppermost packing-ring or gasket is tightly compressed around the closing-plug or stopper such plug or stopper will be firmly held in position and with enough force to prevent its readily being driven or forced out. The plug or stopper is to be driven or forced out by entering the draft-tube E through the hole d in the bung, and in order to enable this to be readily and quickly done

the outer or upper follower C is reversely turned to relieve the compression of the packing-ring or gasket c' on the closing-plug or stopper, so that the plug or stopper will only be nominally held by the inner or lower packing-ring or gasket b' with a force that can be readily overcome in entering the draft-tube through the hole d to insert the draft-tube in the package.

The lower end of the draft-tube passes through the seal, and the seal can be drawn up on the tube without breaking its continuity, thereby enabling the seal to be left intact, and the end of the draft-tube as it strikes the end of the closing-plug or stopper will force such plug or stopper inward, as shown in Fig. 4, in which the end of the draft-tube is entered into the bung and the plug or stopper is partially forced from the bung. The continued advance of the draft-tube to its normal position forces the closing-plug or stopper out of the bung, and its place is taken by the wall of the draft-tube E, and the draft-tube is entered through the bung to the limit required for its lower end to lie adjacent to the bottom of the package, and when in place the opening f' of the passage f will be just below the end of the bung, as shown in Fig. 5, and the nipple g will be above the bung, as shown in Fig. 5, thus furnishing a passage through the tube or conduit F from the outside to the inside of the package without disturbing the liquid in the package or in the draft-tube. After the draft-tube is in position the beer or other liquid can be drawn therefrom in any usual and well-known manner. The empty package before being refilled is to have a new closing-plug or stopper D entered into the bung and the upper follower is advanced to compress the packing-ring or gasket around the closing-plug or stopper, again putting the package in condition to be filled. It will be understood that after the draft-tube E has been inserted to its limit through the bung the upper or outer follower C is advanced to compress the packing-ring or gasket c' around the draft-tube, so as to seal the tube against escape of beer or other liquid and the escape of pressure, and the draft-tube E is removed by reeding the follower C, so as to release the compression of the packing-ring or gasket c' around the tube, thereby enabling the tube to be readily and easily withdrawn from the package.

The bung of the present invention remains a permanent part of the package after it has once been inserted therein, and the only part that is removed in inserting the draft-tube into position is the closing-plug or stopper, with the result that to renew the package for another filling with beer or liquid all that is required is to insert a new plug or stopper. The bung, by reason of the upper and lower packing-rings or gaskets and the upper and

lower followers, can be adjusted so that the lower packing-ring or gasket will exert sufficient pressure to nominally retain the closing-plug or stopper in place without interfering with its being forced out or ejected by the application of a little power in inserting the draft-tube, and the plug or stopper will be effectually sealed by the compression of the upper packing-ring or gasket therearound, and the pressure of this packing-ring or gasket required for sealing can be released by simply receding the upper follower C, so that the forcing out or ejecting of the closing-plug or stopper will not be interfered with by the upper or outer packing-ring or gasket. The two packing-rings or gaskets, with their followers, enable a nominal pressure to be applied around the closing-plug or stopper for holding the plug or stopper in place and a greater pressure to be applied around the plug or stopper for sealing it against the escape of liquid and pressure, and in use the actuating of only the outer or upper follower is all that is required to effect a compression and to release a compression.

The bung is simple in construction, can be readily applied to a package for use, and in use will be found effective, reliable, and positive for enabling a package to be sealed and to allow the closing-plug or stopper to be forced out or ejected. The draft-tube, by reason of the independent tube or conduit for pressure therein, enables pressure to be supplied to the package as required without in the least disturbing the beer or other liquid in the package or in the draft-tube, and this draft-tube can be used with any package having therein the bung, as it is inserted and withdrawn through the same hole in the bung which receives the closing-plug or stopper.

What I claim as new, and desire to secure by Letters Patent, is--

1. In a beer-bung, the combination of a shell having an interior screw-thread and having its interior chamber open at the outer end and terminated at the inner end by a bottom wall having a central hole with an annular recess around the central hole in the inner face of the bottom wall, a packing-ring at the inner end of the chamber of the shell partly entered into the recess and projecting out from the face of the bottom wall, an inner follower located within the chamber of the shell and contacting the inner packing-ring and having a peripheral thread and engaging the interior thread of the shell for the advance of the follower to nominally compress the inner packing-ring around a closing-plug, a packing-ring within the chamber of the shell at its outer end and in contact with the inner follower, and a follower for the outer packing-ring located within the chamber of the shell and contacting the outer packing-ring and having a peripheral thread engaging the interior screw-thread of the shell.

thread of the shell for the advance of the follower to tightly compress the outer packing-ring around the closing-plug, substantially as described.

2. In a beer-bung, the combination of a shell having an interior screw-thread and having its interior chamber open at the outer end and terminated at the inner end by a bottom wall having a central hole with an annular recess around the central hole in the inner face of the bottom wall, a packing-ring at the inner end of the chamber of the shell partly entered into the recess and projecting out from the face of the bottom wall, an inner follower located within the chamber of the shell and contacting the inner packing-ring and having a peripheral thread and engaging the interior thread of the shell for the advance of the follower to nominally compress the inner packing-ring around a closing-plug, a packing-ring within the chamber of the shell at its outer end and in contact with the inner follower, a follower for the outer packing-ring located within the chamber of the shell and contacting the outer packing-ring and having a peripheral screw-thread engaging the interior screw-thread of the shell for the advance of the follower to tightly compress the outer packing-ring around the closing-plug, and a closing-plug having its inner end entered through the central hole in the bottom wall of the shell and having its body passing through alining holes in the packing-rings and followers and around which the packing-rings are compressed for the inner packing-ring to nominally hold the plug in place and for the outer packing-ring to seal the plug, substantially as described.

3. In a beer-bung, the combination of a shell having an interior screw-thread and having its interior chamber open at the outer end and terminated at its inner end by a bottom wall having a central hole, a packing-ring located within the chamber and abutting against the bottom wall of the shell, a ring-follower located within the chamber of the shell and abutting against the inner packing-ring, an outer packing-ring located within the chamber of the shell and abutting against the ring-follower, a washer located within the chamber of the shell and resting on the outer packing-ring, and a ring-follower located within the chamber and abutting against the washer, each ring-follower having an exterior screw-thread engaging the interior screw-thread of the shell and adapted to be moved independently of the other to compress to a different degree around a closing-plug the respective packing-rings on which they operate, substantially as described.

4. In a beer-bung, the combination of a shell having an interior screw-thread and having its interior chamber open at the

outer end and terminated at its inner end by a bottom wall having a central hole, a packing-ring located within the chamber and abutting against the bottom wall of the shell, a ring-follower located within the chamber of the shell and abutting against the inner packing-ring, an outer packing-ring located within the chamber of the shell and abutting against the ring-follower, a washer located within the chamber of the shell and resting on the outer packing-ring, a ring-follower located within the chamber and abutting against the washer, each ring-follower having an exterior screw-thread en-

gaging the interior screw-thread of the shell 15 and adapted to be moved independently of the other to compress to a different degree around a closing-plug the respective packing-rings on which they operate, and a cylindrical closing-plug entered through the 20 holes of the packing-rings, the ring-followers and the washer, substantially as described.
